UNITED STATES PATENT OFFICE.

HENRY J. HEINZ, OF SHARPSBURG, AND ROBERT HOFFMAN, OF PITTSBURG,
PENNSYLVANIA.

SAMPLE-EXHIBITING BARREL-COVER.

SPECIFICATION forming part of Letters Patent No. 445,524, dated January 27, 1891.

Application filed February 6, 1889. Serial No. 298,826. (No model.)

To all whom it may concern:

Be it known that we, HENRY J. HEINZ, of Sharpsburg, and ROBERT HOFFMAN, of Pittsburgh, both in the county of Allegheny and 5 State of Pennsylvania, have invented a new and useful Improvement in Covers for Barrels, &c., of which the following is a full, clear, and exact description.

We shall describe our improvement with 10 reference to the accompanying drawings, in which—

Figure 1 is a perspective view of our improved barrel-cover applied to a barrel. Fig. 2 is a vertical central section of the same. 15 Fig. 3 is a bottom plan view thereof. Fig. 4 is a diametrical edge view of the part 3 of the cover, showing the modified form of flange indicated by dotted lines in Fig. 1.

Like symbols of reference indicate like 20 parts in each.

The object of our invention is to provide a cover of an improved construction for barrels, pails, or boxes for use by grocers and other retail and wholesale dealers for containing goods of a perishable nature and for 25 exposing samples thereof to view without giving free access of air or dust either to the barrel or box or to the sample.

We shall first describe in detail the construction of the cover and shall then indicate 30 specifically the features thereof which distinguish it from covers of the kind previously known or used.

As shown in the drawings, the cover consists of two sections or parts 2 and 3, which 35 are of such shape that when placed together they are adapted to fit the barrel or box to which they are intended to be applied. When intended for use in covering barrels, each of 40 these sections is preferably semicircular in outline and is provided with a downwardly-projecting peripheral flange 4, which may be made to fit either the inside or outside of the barrel and which may be either a complete 45 flange or may be only partial, forming lugs, as indicated by dotted lines in Fig. 1 and full lines in Fig. 4. One of the sections 2 has formed in it a depression or cavity 5, which is designed to serve as a receptacle for holding and exposing samples of the contents of 50

the barrel, this cavity being made integral with the remainder of the part 2, either by molding, casting, or stamping the cover with such cavity. A glass cover is placed over the cavity, and is preferably hinged to the section 55 2 by hinges 10, the pintles *b* of which project from a metal frame or border on the glass, (see Figs. 1 and 2,) though the glass cover may be otherwise applied. The glass cover may be retained in place by a latch 6, 60 as shown in Fig. 2.

In order to provide means for connecting the sections 2 and 3, so that one may be raised, as on a hinge, independently of the other for the purpose of exposing the contents of the 65 barrel, we provide the straight side of one of the sections—say the section 2—with horizontally-projecting loops 7, which are preferably made integral with the section 2, and on the other section 3 we form corresponding projecting hooks 8, which are adapted to fit within the loops 7, as shown in Figs. 2 and 3. These loops and hooks are preferably formed on the under side of the sections of the cover, so that when the cover is in place they are not exposed 75 to view. They enable either of the sections to be raised as on a hinge and to be easily removable from the other. At the meeting line of the cover-sections one of them has a flange or projecting portion *c*, which fits under the edge of the other section for the purpose of excluding dust and vermin from the 80 barrel.

In applying the cover to use the sections 2 and 3 are set on the barrel, as shown in Figs. 85 1 and 2, and the flanges or lugs 4, fitting outside of the barrel, hold the cover firmly in place, obviating the necessity for the use of special fastening appliances.

Samples of the contents of the barrel are 90 placed in the cavity 5, and when this is covered by the glass lid air and dust are excluded therefrom; but by removing the lid the samples may be taken out without uncovering the barrel. We prefer to cast the 95 two sections of the cover of iron; but they may be made by stamping or otherwise forming metal or other material suitable for the purpose. If desired, the cover may be suitably enameled or japanned, either on its en- 100

tire surface or on the sample-cavity 5 alone. In adapting a cover for use on boxes, pails, &c., the construction remains the same, the external shape and size being altered to suit 5 the shape and size of the vessel with which it is used.

We are aware that we are not the first to use sectional barrel-covers provided with a sample-exhibiting glass-covered receptacle; 10 but such receptacle has heretofore consisted of a removable drawer or tray formed separate from the cover, and in order to get access thereto the cover must be removed.

We claim as our invention--
15 The sections 2 and 3, having depending

flanges or lugs 4, one of the sections being provided with a sample-exhibiting cavity, the meeting edges of the sections overlapping, and the loops 7 and hooks 8 for detachably hinging together the sections, substantially 20 as and for the purposes described.

In testimony whereof we have hereunto set our hands this 2d day of February, A. D. 1889.

HENRY J. HEINZ.
ROBERT HOFFMAN.
